POWER MOWER

Anthony Sarlo, P.O. Box 1169,
Fort Myers, Fla. 33902

Filed May 10, 1967, Ser. No. 7,063

Term of patent 14 years

(Cl. D40—1)

Fig. 1

Fig. 2

Fig. 3

Fig. 4

Fig. 5

Fig. 6

Fig. 7

Fig. 8

FIGURE 1 is a side elevational view of a power mower, showing my new design;

FIGURE 2 is a bottom plan view thereof;

FIGURE 3 is a top plan view thereof;

FIGURE 4 is a rear view thereof;

FIGURE 5 is a front view thereof;

FIGURE 6 is a front perspective view of a modified form of the power mower illustrated in FIG. 1;

FIGURE 7 is a rear view thereof; and

FIGURE 8 is a front perspective view of the power mower illustrated in FIG. 1.

The power mower motor has been omitted in FIGS. 4, 5 and 7 for ease of illustration.

I claim:

The ornamental design for a power mower, as shown and described.
